UNITED STATES PATENT OFFICE.

JOHN A. BERTRAND, OF LOS ANGELES, CALIFORNIA, ASSIGNOR, BY DIRECT AND
MESNE ASSIGNMENTS, OF ONE-HALF TO ASBURY REED, OF LOS ANGELES, CALI-
FORNIA, AND ONE-HALF TO WEHNER A. KOCH, OF SAN FRANCISCO, CALI-
FORNIA.

ABRASIVE EXPANSION REAMER.

Application filed March 15, 1921. Serial No. 452,617.

To all whom it may concern:

Be it known that I, JOHN A. BERTRAND, a citizen of the United States, residing at Los Angeles, in the county of Los Angeles 5 and State of California; have invented new and useful Improvements in Abrasive Expansion Reamers, of which the following is a specification.

It is the object of this invention to provide an abrasive reamer having means for readily expanding the circumference defined by the abrasive material.

It is a still further object of the invention to provide a reamer having a readily expandible and contractable guide sleeve which carries detachable plugs of abrasive material.

The invention will be readily understood from the following description of the accompanying drawings, in which

Figure 1 is a side elevation of a reamer constructed in accordance with the invention.

Fig. 2 is a longitudinal section on the line 25 2—2 of Fig. 1.

Fig. 3 is a transverse section on the line 3—3 of Fig. 1.

The reamer includes a mandrel which is formed with a tapering portion 1 and end 30 projections 2 and 3, one of which is threaded as shown at 4 in order to receive a usual coupling, while the other end projection 2 is preferably provided with a flattened surface portion 5 in order that it may be readily engaged by a wrench.

A guide sleeve 6 is received upon the tapering portion 1 of the mandrel, and the entire surface of this guide sleeve forms a tapering bore co-operating with the taper 40 of the mandrel. The guide sleeve is of somewhat resilient material and is arranged for expansion and contraction by providing series of slots 7 and 8 extending lengthwise of the guide sleeve from the respective ends 45 thereof. The slots terminate short of the opposite ends of the guide sleeve and are preferably provided with circular enlargements 9 at their inner ends. By this arrangement it will be seen that the guide sleeve may be readily expanded and contracted upon the mandrel by adjusting the sleeve longitudinally of the tapering portion of the mandrel so as to cause engage-

ment between the co-operating tapering surfaces of the mandrel and guide sleeve. 55

In order to prevent rotary movement of the guide sleeve upon the mandrel while permitting of longitudinal adjustment of the sleeve, keys 10 are preferably fixed to the mandrel and are received within either 60 slots 7 or 8 of the guide sleeve. In order to longitudinally shift the guide sleeve, the latter is preferably provided with an in-turned flange 11 at its larger end and received around the end projection 3 of the 65 mandrel. A nut 12 is threaded on to the end projection 3 of the mandrel so as to impinge against flange 11 and thus provide for longitudinal adjustment of the guide sleeve. The nut 12 may be provided with suitable 70 apertures 13 adapted to be engaged by a tool for rotating the nut.

The guide sleeve of the reamer carries a plurality of plugs of abrasive material 75 which are preferably readily detachable from the guide sleeve and replaceable when worn. For this purpose a plurality of apertures 15 is provided in the guide sleeves, and plugs 16 of suitable abrasive material are received in these apertures so as to project radially beyond the guide sleeve. The plugs are preferably provided with enlargements 17 at their inner ends which are received within the countersunk portions 18 at the inner ends of apertures 15 so as to hold 85 the plugs against radial displacement and permit of the ready removal and renewal of the same when the guide sleeve is removed from the mandrel.

In order to readily remove the expandible 90 guide sleeve from the tapering mandrel after the completion of a piece of work and when the sleeve has been forced down tightly upon the mandrel to fully expand the sleeve, a nut 19 is preferably threaded upon the 95 large end of the tapering mandrel which projects somewhat beyond the end of the guide sleeve. It will thus be seen that by screwing nut 19 onto the mandrel, the guide sleeve may be forced from the same.

It will thus be seen that I have provided an extremely simple but efficient abrasive reamer wherein a guide sleeve carrying the abrasive material is adapted to be readily expanded as the reaming continues.

Various changes may be made without

departing from the spirit of the invention as claimed.

What is claimed is:

1. A reamer including a mandrel, an expandible guide sleeve mounted thereon, said sleeve being provided with a plurality of apertures, plugs of abrasive material removably mounted in said apertures so as to project radially beyond the sleeve, and 10 means for expanding and contracting said sleeve.

2. A reamer including a mandrel, a guide sleeve mounted thereon and having longitudinal slots spaced circumferentially to 15 permit of uniform expansion and contraction of said sleeve, keys carried by said mandrel and received in said slots for locking the latter against rotational movement on the mandrel, abrasive plugs mounted in the

sleeve between said slots, and means for expanding and contracting said sleeve.

3. A reamer comprising a mandrel, an expandible sleeve mounted thereon and having openings therein, and abrasive plugs fitted within said openings, and means for 25 locking the plugs against displacement from the openings.

4. A reamer comprising a mandrel, an expandible sleeve mounted thereon and having openings formed therein, plugs fitted 30 within said openings, and flanges carried by the plugs and adapted to be interposed between the mandrel and sleeve for locking the plugs within the openings.

In testimony whereof I have signed my 35 name to this specification.

JOHN A. BERTRAND.
